UNITED STATES PATENT OFFICE.

CHARLES R. HOWARD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

PATTERN-CHAIN GUIDE FOR LOOMS.

Application filed September 15, 1926. Serial No. 135,653.

This invention relates to improvements in guides for pattern chains such as are used for the box motions of multi-color looms and it is the principal object of the invention to provide a guide so designed as to permit the reversal of the pattern chain and the formation of the chain with a series of loops.

Certain repeats of intricate patterns call for a large number of bars on the box chain and in order to nest the chain conveniently and economically there is frequently used a guide and support for the chain, certain bars of the chain located at intervals being of increased length to rest on the support and the shorter bars passing through the support to form loops, thus making it possible to accommodate a long chain in a comparatively small space. Some fabrics have a repeat which is symmetrical about a center line and it is possible because of this symmetry to reverse the pattern chain after one-half of the repeat has been woven. I find that the long bars of the chain which are spaced to rest on a guide will occasionally slip off the guides and as the chain moves around the chain cylinder the long bar will in time come up on the under side of the guide. When the chain in this position is moving in a forward direction the long bar will ordinarily be able to move upwardly from under the chain guide without difficulty, but when the chain is reversed so that the stretch of chain moving toward the cylinder is substantially vertical I find that the long bar is likely to break either a part of the pattern chain or a part of the guide. It is accordingly a further object of my invention to provide a pattern chain guide or support having a yielding portion so located as to support the long bars when the latter are moving in one direction and yieldable upwardly to permit easy passing of the long bars when the chain is reversed and a long bar has accidentally fallen below the guide.

With these and other objects in view which will appear as the description proceeds, my invention resides in the combination and arrangement of parts hereinafter described and set forth in the claims.

In the accompanying drawings wherein I have shown a convenient embodiment of my invention,

Fig. 1 is a central vertical section through the chain guide having my invention applied thereto and showing a portion of the loom frame on which the same is mounted, 55

Fig. 2 is a vertical section on line 2—2 of Fig. 1, 60

Fig. 3 is a fragmentary diagonal top plan of that portion of the chain guide having my invention applied thereto,

Fig. 4 is a detail side elevation of one end of the yielding guide, and 65

Fig. 5 is a view similar to a portion of Fig. 1 but showing the yielding part moved outwardly to permit the passage of an improperly positioned long bar.

Referring more particularly to the drawings frame 10 of the loom is provided with an arm 11 to which is secured a shaft 12 for a chain cylinder 13. The latter may be driven in any approved manner by mechanism not shown and will ordinarily receive an angular movement each pick of the loom to advance the chain 14 one space at a time. Said chain is formed with a plurality of links 15 lying on each side of the chain and connected together by means of bars the 70 great majority of which are of the short form shown at 16 in Fig. 2 and a few of which are longer and located in pairs at 75 periodic intervals in the length of the chain as indicated at 17. The bars have mounted 80 thereon so-called balls 18 and sinkers 19 which determine the vertical position of 85 indicating levers not shown but of any usual form, said levers being operatively connected to the boxes of the loom. 90

In order to support and nest the relatively long chain there is provided a guide 20 having a cross web 21 secured to the frame 10 by means of bolts 22, one of which is shown in the drawings, and having spaced 95 substantially parallel runs 23 with upwardly projecting chain bar supporting flanges 24. Vertical arms 25, one for each side of the guide, support a rod 26 to which is secured a plate 27 on which the upper stretch 100 or portion of the chain normally rests.

As the cylinder 13 is rotated the chain 14 is moved thereby, the greater part of the bars 16 passing down between the guides 23 but the bars 17 of increased length resting 105 on the flanges 24 so that the chain is formed in loops as indicated at the bottom of Fig. 1. The matter thus far described is of com-

mon construction and forms no part of my present invention.

In carrying out my improvements I provide a portion of each run 23 with a yielding spring member 30 which is flexible and has riveted to one end thereof a block 31 screwed to a portion of the run as at 32, the upper surface of the spring member 30 aligning with the top of flange 24 so as to provide a smooth surface along which the long bars 17 may slide. The upper end of each of the spring members 30 is supported as at 33 by a part of the frame 20, being received by a slight notch 34 in said frame so that the upper surface of said members 30 may be flush with those parts of the runs on which the long bars slide.

When the chain is moving around the cylinder in a right hand direction the bars 17 will move down almost in a vertical line and will be guided along the yielding supports 30 onto the flanges 24, this downward motion of the right hand part of the chain being accompanied by an upward movement of the left hand part of the chain. Should a long bar 17 slip down between the flanges 24 by becoming twisted it will be able to move upwardly along the surface 35 of the runs and no harm will result. When the chain is reversed, however, so as to go in a left hand direction around cylinder 13 and a long bar 17 accidentally falls below the runs it will eventually be lifted against the under side of the yielding supports 30, at which time the latter will be flexed to the position shown in Fig. 5 to permit the long bar 17 to move upwardly toward the cylinder without damage to the guide.

From the foregoing it will be seen that I have provided a chain guide or support with runs parts of which are flexible to yield under pressure when one of the long bars of the chain which is improperly positioned arrives thereunder and that said yielding part normally serves as a part of the guide when the chain is moving in the opposite direction.

Having thus described my invention, it will be apparent that changes and modifications may be made therein by those skilled in the art without departing from the spirit and scope of the invention, and I do not wish to be limited to the details herein disclosed but what I claim is:

55. 1. In a chain guide or support for a loom having a pattern cylinder and a chain for

the cylinder certain bars of which are longer than other bars, a pair of spaced supporting runs to support the longer bars, and flexible means interposed in the runs to flex upwardly to permit a portion of the chain to move toward the cylinder when one of the long bars is improperly located below the runs.

2. In a chain guide for a loom having a pattern cylinder and a pattern chain for the cylinder certain bars of which are longer than other bars, said guide having means located under the cylinder to receive and support the longer bars of the chain, and flexible portions for the means to support the long bars when traveling in either direction over the means and yieldable upwardly when a long bar improperly located below the means engages the flexible portions when moving toward the cylinder.

3. In a chain guide for a loom having a pattern cylinder and a pattern chain for the cylinder certain bars of which are longer than other bars, said guide having means located under the cylinder to receive and support the longer bars of the chain, and flexible portions for the means to support the long bars when travelling in either direction over the means and yieldable upwardly when a long bar improperly located below the means engages the flexible portions when moving toward the cylinder, the top portions of the flexible portions being in alignment with adjacent parts of the means to provide smooth guiding surfaces for the ends of the long bars on the chain.

4. In a chain guide for a loom having a pattern cylinder and a pattern chain certain bars of which are longer than other bars, a pair of spaced runs to receive and support the longer bars of the chain, and a flexible device forming a part of the guides and secured to the latter and extending upwardly from the point of attachment to the guides toward the cylinder, the upper ends of the portions adjacent the cylinder being supported by parts of the guides, said flexible portions yielding when engaged on the under side thereof by one of the long bars improperly located below the runs as the improperly located bar moves toward the cylinder.

In testimony whereof I have hereunto affixed my signature.

CHARLES R. HOWARD.
